DRAWERS

Edmund Gurney, Long Beach, Calif.

Application January 25, 1935, Serial No. 3,414

1 Claim. (Cl. 2-224)

This invention relates to wearing apparel and particularly to men's drawers of the type commonly termed "shorts".

A broad object of the invention is to increase the durability of garments, the major portions of which are made of relatively inexpensive materials.

A more specific object is to so reinforce a pair of drawers that they can be constructed of material having relatively low resistance to tearing and still give good service.

The manner in which the foregoing objects are achieved, together with other objects and features of the invention, will now be explained with reference to the drawings, in which

Fig. 1 is a front view of a pair of drawers constructed in accordance with the invention;

Fig. 2 is a rear view of the same garment;

Fig. 3 is a plan view of a reinforcing element used to strengthen the fly and crotch of the garment;

Fig. 4 is a plan view of another reinforcing element employed on the opposite fly to that on which the element shown in Fig. 3 is employed;

Fig. 5 is a plan view of the front portion of one of the side panels of the garment;

Fig. 6 is a plan view of the front portion of the other side panel of the garment; and

Figs. 7, 8, 9, 10 and 11 illustrate the successive steps involved in sewing together the elements shown in Figs. 3, 4, 5 and 6, in making the garment.

As generally constructed, men's shorts are composed of either two or three pieces. Thus the garment shown in the drawings comprises three main pieces consisting of a left side panel 1, a right side panel 2 and a rear panel 3. The manner in which these three elements are combined, considered as units, is well known and is clearly illustrated in Figs. 1 and 2.

The garment disclosed differs from prior known garments in that the rear panel 3 is bias cut so that the threads of this piece run diagonally instead of vertically and horizontally, as in the side panels 1 and 2. I have found this construction to be of great advantage in that the bias cut panel 3 affords resilience in a circumferential and in a vertical direction, which permits the garment to yield sufficiently in response to movements of the wearer to prevent tearing strains which might otherwise result.

Another novel feature of the garment disclosed in Figs. 1 and 2 lies in reinforcing elements 4 and 5 which extend along the fly margins of the side panels 1 and 2 and reinforce the material ad-

jacent the seam between these elements at the crotch of the garment. The reinforcing elements 4 and 5 greatly increase the resistance of the garment to tearing at the crotch by virtue of the fact that they are individually sewn to their associated side panels 1 and 2, respectively, prior to the joinder of the latter.

The shape of the reinforcing element 5 prior to its incorporation into the garment is shown in Fig. 3 and the shape of the reinforcing element 4 is shown in Fig. 4. The margins of these elements 4 and 5 correspond in shape to the margins of the side panels 1 and 2, respectively, the latter being illustrated in Fig. 6 and Fig. 5, respectively. The reinforcing element 5 is first secured to the side panels 2 by laying the element 5 on the panel 2, as shown in Fig. 7, and sewing the two together closely along the margin, as shown at 7. Thereafter the parts are reversed by folding them back about the seam 7 and again stitching the two together at the stitching 8 shown in Fig. 9. It will be observed that the stitching 8 follows very closely the margin of the reinforcing element 5 except along the length (a) in Fig. 9, at which point the stitching is preferably spaced about a quarter of an inch inwardly from the margin for a purpose to be described.

The reinforcing element 5 is similarly attached to the side panel 1 of the garment first by stitching the two together along their outer margins, as shown at 9 in Fig. 8, then reversing the parts about the seam 9 and stitching them together all around the margin, as shown at 10 in Fig. 10.

The two units, one comprising the side panel 2 and its reinforcing element 5, as shown in Fig. 9, and the other comprising the side panel and its reinforcing element 4, as shown in Fig. 10, are then combined by stitching them together along the length (a), as shown in Fig. 11. During this sewing operation the inwardly spaced stitching 8 on the panel 2 serves as a guide to the operator, the edge of the corresponding portion (a) of the panel 1 being maintained close to the stitching 8 over the corresponding portion (a) of the panel 2 during the sewing operation.

Following the joinder of the side panels 1 and 2 to each other at the crotch, as shown in Fig. 11, the two parts are sewed to each other and to the rear panel 3 to complete the garment in accordance with well established practice which is too well known to those skilled in the art to merit detailed description. Observation of the seams of the completed garment as shown in Fig. 1 is sufficient to inform any tailor how the remaining seams of the garment are formed.

I have determined by careful investigation and experiment that the crotch is the weakest point of a garment of the type described and that the garment is much more apt to tear or rip apart adjacent the upper end of the crotch seam (as indicated at (a) than anywhere else. By reinforcing this area in the manner described with the reinforcing strips 4 and 5, the strength of the garment at this point of weakness may be so greatly increased that the side panel portions 1 and 2 of the garment may be made of very inexpensive material while at the same time yielding a garment that is actually stronger and more durable than those made in accordance with former practice from much stronger materials.

Still another feature of the invention resides in the use of buttonholes 11 positioned in the waistband of the garment for attaching the garment to the suspender buttons of the trousers of the wearer. I preferably provide at least two or more buttonholes 11 on each side of the garment, as shown in Fig. 1, to permit adjustment to take care of varying spacing between the suspender buttons on different trousers.

Still another feature of the invention resides in the use of tape loops 12 (Fig. 2) in combination with buttons 13 for providing an adjustment of the waistband dimensions of the garment. It has been common practice heretofore to provide tapes which would be tied together for reducing the waistband, or elastic inserts. I have found that it is highly desirable in a garment of this general type to provide additional fullness below the waist by inserting darts 13' at the waistband. I have found that the loops 12 may be attached to the waistband with practically no additional labor by sewing the ends of the loop into the folds of the darts 13 at the time the latter are formed. Thereafter substantially the only additional labor required is to attach the buttons 13 and this can be done very inexpensively.

As a result of the various features described in

detail hereinabove, I am able to construct drawers having strength and durability of similar garments heretofore known at a greatly reduced cost by virtue of the fact that these features enable me to employ materials which are much less expensive than those heretofore considered necessary.

Although the invention has been described specifically as applied to the construction of men's drawers, it is obvious that there are other garments involving points of strain which might be reinforced in the manner described, such applications being apparent to those skilled in the art, and the invention is therefore to be limited only as set forth in the appended claim.

I claim:

The method of joining the front panels constituting the opposite sides of the fly of a crotch fitting garment to each other and to a pair of reinforcing strips extending along the fly margins 20 of the panels, consisting of positioning each of said reinforcing strips on its associated panel member with their fly edges in registration and sewing them together closely adjacent their fly edges, then reversing each strip and panel about 25 said sewn edge, then sewing each strip to its associated panel along each edge of the strip of stitching closely adjacent the margin of the reinforcing strip except along that portion of the margin of one strip which is to be overlapped by 30 the other panel when the two are sewn together, the stitching along said portion being spaced from the edge a distance slightly greater than the overlap of the other panel, whereby the stitching serves as a guide to gauge the amount of overlap 35 when the panels are later sewed together, and thereafter sewing each panel as a unit with its associated reinforcing strip to the other panel, the reinforced portions of the panels overlapping each other adjacent the crotch of the garment. 40
